UNITED STATES PATENT OFFICE.

JACOB TEODOR JACOBSON, OF BROOKLYN, NEW YORK.

BROOM CLAMP.

Application filed July 18, 1922. Serial No. 575,837.

To all whom it may concern:

Be it known that I, JACOB T. JACOBSON, a citizen of the United States, and a resident of the city of New York, borough of Brooklyn, in the county of Kings and State of New York, have invented a new and Improved Broom Clamp, of which the following is a full, clear, and exact description.

This invention relates to a broom clamp, and has for an object the provision of a simple, efficient and durable device which can be readily applied to a broom, and as easily removed therefrom, to adjustably clamp the fibers or straws of the broom at any point along the length thereof so that the broom fibers can be held more or less firmly, as desired.

Another object resides in the provision of latching means in connection with the clamp so that the degree to which the fibers are held by the clamp can be very readily adjusted and as easily released.

A further object resides in the particular construction and arrangement of parts which are hereinafter described and claimed and shown in the accompanying drawings.

The invention is illustrated in the drawings, of which—

Figure 1 is an elevation of a broom with the clamp applied.

Fig. 2 is an enlarged elevation of the clamp;

Fig. 3 is a section taken on the line 3—3 of Fig. 2; and

Fig. 4 is a partial elevation showing the parts in their locked position.

The form of the invention shown in the drawings is the preferred form, although it is understood that modifications in the construction and arrangement of the parts and in the character of the materials used may be adopted without departing from the spirit of the invention.

The invention as illustrated in the drawings discloses a preferred form of the invention and includes a pair of U-shaped straps the free ends of the limbs of which are adapted to lie against each other and be adjustably engageable so as to clamp the fibers of the broom between themselves.

As shown in the figures, the invention comprises a pair of U-shaped straps 1 and 2 each of which is provided with limb portions 3 and 4, respectively. The limb portion 3 of each strap is provided with one or more headed members or pins such as 5 and

6. The limb portion 4 of each strap is provided with a slot such as 7 extending to the end of the limb portion. This slot in each limb portion 4 is provided with a plurality of enlarged portions 8 in which the pins 5 are adapted to be disposed. There are a plurality of these enlarged portions 8 throughout the length of the slot 7.

The end of the limb portion 4 of each strap is provided with upturned flanges such as 9 and 10, and pivoted to these flange members is a latching plate 11. This arrangement, as previously stated, is formed on the end of each limb member 4. It will be noted from Figs. 2 and 4 that the flange members 9 and 10 are disposed at a slight angle to each other. Normally when the latching member 11 is disposed in the position shown in Fig. 2, extending away from the end of the limb 4, the ends of the limb are normally spaced and when the latching member 11 is moved into the position shown in Fig. 4 the flanges 9 and 10 are engaged by the side members 12 and 13 of the latching member 11; and by reason of their angular relation, the ends of each limb 4 will tend to be contracted so that the sides of the slots 7 will firmly embrace the stems of the headed members 5 to firmly hold the two strap members together. It is understood that this clamping action is somewhat similar to a cam action. When the parts are in the normal position the slot is of normal size, but when the parts are in clamped position the diameter of the slot is reduced. It is also understood that the limb member 4 of each strap having the slot portion lies adjacent the limb member 3 of the other strap, said limb member 3 having the headed members thereon.

It will be observed that I have provided a simple, efficient and easily applied device which will firmly grip the straws of a broom at any desired level to hold them in a compact manner. The device is very easily applied by merely pressing the two straps together until the proper position is assumed, when the latching action can take place as above described. The pressure of the broom straws themselves will hold the latch in its operative position until it is definitely released.

What I claim is:

1. A broom clamp which includes a pair of U-shaped straps adapted to embrace the straws of a broom, one end of one of said

straps having a slot therein, a headed projection extending from the adjacent end of the other strap through said slot, and means on the end of the first-mentioned strap the movement of which means will contract the sides of the slot on the said headed projection to hold the ends of the straps together.

2. A broom clamp which includes a pair of U-shaped straps adapted to embrace the straws of a broom, one end of each of said straps having a slot along its length provided with enlarged portions, a headed projection adapted to extend from the adjacent end of the other strap through said slot and to lie in any one of said enlarged portions, the slotted ends of the straps being separated, and cam means associated with the ends of the strap to draw the ends together whereby the sides of the slot will be contracted on to the headed projection to hold the ends of the straps together.

3. A broom clamp which includes a pair of U-shaped straps adapted to embrace the straws of a broom, one end of each of said

straps having a slot therein, said slot along 25 its end provided with enlarged portions, a headed projection on the opposite end of the adjacent strap adapted to extend through the slot and to lie in any one of said enlarged portions, the slot in one end of each 30 strap extending to the end of said strap, flanges formed on the ends of said slotted portion and extending at right angles to the surface of the strap, said flanges being angularly disposed with respect to each other, 35 and a latch plate pivoted to said flanges having side members engageable therewith, said latch plate in normal position extending away from the end of said strap and in its operative position being bent upward 40 along the strap, the engagement of the side members of the latch plate with the flanges bringing about a cam action which will collapse the sides of the slot in the strap on the headed projections or members of the other 45 end of the other strap.

JACOB TEODOR JACOBSON.
